H. R. GRANT.
METHOD FOR FILING PRINTING PLATES.
APPLICATION FILED NOV. 13, 1919.

1,415,629.

Patented May 9, 1922.

UNITED STATES PATENT OFFICE.

HARLO R. GRANT, OF CHICAGO, ILLINOIS.

METHOD FOR FILING PRINTING PLATES.

1,415,629.

Specification of Letters Patent.

Patented May 9, 1922.

Application filed November 13, 1919. Serial No. 337,853.

To all whom it may concern:

Be it known that I, HARLO R. GRANT, a citizen of the United States, residing at Chicago, in the county of Cook and State 5 of Illinois, have invented certain new and useful Improvements in Methods for Filing Printing Plates, of which the following is a full, clear, concise, and exact description, reference being had to the accompanying 10 drawing, forming a part of this specification.

My invention relates to improvements in means and method for filing printing plates. The objects of my invention are:

15 First: to provide a novel method of storing printing plates whereby the plates will be protected against dust and dirt and mechanical injury.

Second: to provide a method of the character described which will permit the cuts to be filed and indexed so that they may be easily located when desired.

25 Third: to provide means of the character described which will require a minimum amount of space and which is economical to manufacture.

Fourth: to provide a novel method of storing or filing printing plates whereby they are protected against warping.

30 Other objects will definitely appear as this description progresses, reference being had to the accompanying drawings, in which—

Figure 1 is a front elevation disclosing a plurality of the files which I employ in carrying out my method and which are housed in a suitable casing or cabinet, this view disclosing a front end elevation of the files;

Figure 2 is a plan view on an enlarged scale of one of my improved files, the cover 40 being partially open to disclose the manner in which the plates are filed;

Figure 3 is a transverse section taken on line 3—3 of Figure 2;

Figure 4 is a broken longitudinal section 45 on line 4—4 of Figure 2;

Figure 5 is a broken longitudinal section showing a modified form of file; and

Figure 6 is a plan view showing another modified form of file, portions thereof being 50 broken away.

Throughout the specification similar reference characters will be used for referring to similar parts.

Heretofore, so far as I am aware, it has 55 been customary in large printing establish-

ments to file printing plates in a haphazard manner, the plates being stored away in a horizontal position, one on top of the other in boxes, various sorts of files, etc., no attempt being made to prevent mechanical injury 60 of the printing surface of the plate by preventing this surface from being struck by adjacent plates, and no attempt being made to secure even exposure of the surface of the wooden backing to the air, to insure the 65 cuts against warping.

Furthermore, so far as I am aware, no means have ever been provided where the plates can be thoroughly indexed so as to make it easy to locate any given plate when 70 it is desired. The objects of my invention, are as stated above, to correct these defects in prior storage method.

Another object of my invention is to provide a method of storing the plates so that 75 any desired plate can be easily and quickly selected from a plurality of plates filed in the same container.

Referring to the drawings, the reference character 10 indicates a casing or cabinet 80 which can be constructed in any desired manner, but which is preferably made in sections which can be superimposed upon each other to form a vertical cabinet of a plurality of units. The reference characters 11 indicate 85 a plurality of my improved files which, as shown, are constructed so that they may be assembled in the cabinet on edge, as illustrated in Figure 1, for a reason which will be referred to later on.

90 The file illustrated in Figures 2, 3 and 4 comprises a bottom piece 12, side pieces 13, a front end piece 14 and a rear end piece 15, which together form a rectangular file which may be closed by the cover 16. The 95 upper edges of the side pieces 13 are flanged inwardly as shown at 17, and the flanges are then bent outwardly upon themselves, as shown at 18, thereby providing a slideway for the overturned edges 19 of the cover, this 100 slide serving to support the cover and preventing its forward end from dropping into the file. The forward end of the cover may be bent upon itself, as shown at 20, to provide a stiffening member and the rear 105 end may be similarly conformed or a stiffening bar 21 may be secured thereto in any desirable manner. The forward end of the file is preferably provided with a handle or finger piece 22 by means of which the 110

file can be withdrawn from the cabinet and is also provided with a cardholder 23 for receiving a suitable indexing card or label.

With the construction just described the 5 printing plates 24 may be placed in the files in edgewise vertically superimposed relation, the files being sufficiently deep to leave a 10 space between the wooden backings of the plates and the bottom of the file, thereby permitting even distribution of air over the 15 back sides of the plates, and thereby insuring even drying of the wooden backings, so that the plates will not warp. Furthermore, each lower plate acts as a support having a 20 horizontal upper surface for each of the plates superimposed thereon, whereby the superimposed plates are supported substantially vertically, so that there will be no 25 tendency for these plates to warp, as there would be if they were stored in an inclined 30 position. Furthermore, by storing the plates in superimposed relation, as described, with their printing faces exposed when the cover is opened, each plate is visible so that it can 35 be readily located and removed from the file without disturbing the remaining plates for the purpose of locating that particular plate. With my particular means and method for storing plates there is no danger whatever 40 of the printing surfaces of the plates being ruined by being brought into contact with adjacent plates. Other advantages will readily occur to those having knowledge of the printing art and of the methods which are now used for storing plates for future use.

Figure 5 shows a modified form of file in which the rear end of the file is not provided with an integral closure, but in which 45 the cover 16' is provided with a flange 25 for closing the rear end of the file. With this construction when the file is withdrawn from the cabinet and the cover is completely removed the plates can be removed from the 50 file simply by bringing the bottom of the file into a position flush with an imposing stone, or any other suitable surface, and sliding the plates from the file onto the stone. The plates may also be returned to the file 55 by the reverse of this process. The cover 16' is provided with an opening 26 for receiving a finger for the purpose of opening the cover.

The construction illustrated in Figure 6 55 shows a modified form of the cover 16'

shown in Figure 5. With a construction similar to that shown in Figure 5 it is possible that in pulling upon the handle or knob 22 to remove the file from the cabinet the weight and inertia of the plates might 60 be sufficient to cause the cover 16' to remain in the cabinet as the file is being withdrawn, thereby permitting the plates to slide from the rear end of the file or possibly to drop out of the file. In the embodiment shown in 65 Figure 6 the front end of the cover is provided with a projection 22' having opening 30 therein for receiving a finger. This projection, when the cover 16' is closed, projects through a suitably shaped slot in the front 70 end of the file and forms a handle or finger-hold by means of which the file can be withdrawn from the cabinet. Since the force exerted upon the file to remove it from the cabinet is transferred through the projection 75 22' there will be no chance for the cover 16' to open rearwardly.

It will be noted that the covers of my improved files all open rearwardly, which makes it possible to inspect the contents of 80 the file before it is entirely withdrawn from the cabinet.

With the construction embodying the ideas above described it is possible to so index the files that any given plate desired can be 85 readily located with a minimum expenditure of time and energy, and at the same time the plates are thoroughly protected against mechanical injury, dust and warping.

While the files and cabinet may be constructed of any suitable material, I prefer to have them constructed of metal because 90 of its fireproof qualities, and because it can be economically employed in the manufacture of the files.

Having thus described my invention, what I claim as new and desire to secure by United States Letters Patent is:

The method of preserving printing cuts, 100 which comprises arranging said cuts in vertical superimposed relation, and confining them in a narrow container so as to leave a slight air space between the backs of said cuts and the adjacent walls of the container.

In witness whereof, I hereunto subscribe 105 my name this 3d day of November, 1919.

HARLO R. GRANT.

Witnesses:

MARY A. COOK,

ANDREW WINTERCORN.
